UNITED STATES PATENT OFFICE.

ADOLPH W. BERKNER, OF CAYUGA, NORTH DAKOTA.

ELEVATOR-BUCKET.

No. 873,655.

Specification of Letters Patent.

Patented Dec. 10, 1907.

Application filed March 26, 1907. Serial No. 364,667.

To all whom it may concern:

Be it known that I, ADOLPH W. BERKNER, a citizen of the United States, residing at Cayuga, in the county of Sargent and State 5 of North Dakota, have invented new and useful Improvements in Elevator-Buckets, of which the following is a specification.

This invention relates to buckets intended for use in grain elevators, and it relates more 10 particularly to a bucket construction, whereby the overloading of the bucket is prevented.

The invention has for one of its objects to improve and simplify the construction of devices of this character so as to be comparatively 15 easy and inexpensive to manufacture, of substantial and durable design, and reliable and efficient in use.

A further object of the invention is the provision of an elevator bucket that is 20 equipped with a yieldingly supported bottom that is adapted to open under the weight of an excessive amount of material and automatically closed when the weight or quantity reaches a certain predetermined amount so 25 that the buckets of the elevator will each deliver accurate amounts.

With these objects in view and others, as will appear as the description proceeds, the invention comprises the various novel features 30 of construction and arrangement of parts as will be more fully described herein-after and set forth with particularity in the claims appended hereto.

In the accompanying drawing, which illustrates 35 one of the embodiments of the invention, Figure 1 is a perspective of the bucket. Fig. 2 is a transverse section showing the bottom closed and opened by full and dotted lines respectively.

Similar reference characters are employed 40 to designate similar parts throughout the several views.

Referring to the drawings, 1 designates the body of the bucket that is preferably made 45 of sheet metal and bent to form a vertical back wall 2 and sector shaped end walls 3 disposed laterally with respect to the back wall, the top edges of the end walls 3 being disposed at an oblique or acute angle with 50 respect to the vertical, as shown in Fig. 2. Disposed between the ends 3 is a bottom plate 4 arranged downwardly inclined toward the bottom edge of the back wall 2, and overlapping the said bottom edge so that the 55 latter forms a stop against which the bottom plate is normally held. Around the upper

edge of the bucket is a metal rectangular band 5 which, in addition to giving stability and strength to the bucket, forms a support to which the bottom plate is attached. The 60 front portion 6 of the band 5 has secured thereto a flexible strip of leather, spring metal or other material 7 that is backed by a metal strip 8. To the bottom free edge of the flexible member 7 is riveted or otherwise 65 suitably secured the upper edge of the bottom plate 4. By flexibly supporting the bottom plate, the latter can swing outwardly away from the back 2 so as to discharge material from the bottom of the bucket. The 70 bottom 4 is normally held in place by an arcuate leaf spring of steel or other spring metal designated by 9, the upper end being riveted to the center of the front portion 6 of the encircling reinforce or band 5 with the 75 lower end of the spring resting against the bottom extremity of the plate 4. The spring is so proportioned that it will hold the bottom of the bucket closed under the weight of a predetermined amount of grain or other 80 material picked up by the bucket. As for example, when the bucket is filled perfectly level, the bottom will remain closed, but should the material be heaped up on the top, the weight would be sufficient to cause the 85 bucket to swing open against the tension of the spring 9 until the weight has diminished sufficiently to permit the bottom to automatically close. In this manner, each bucket will transport a predetermined amount so 90 that the material transported by the elevator for a given length of time or numbers of turns of the endless belt or conveyer thereof, can be accurately ascertained.

The use of a hinge in the form of a flexible 95 strip as described, is a special feature of the present invention for the reason that the strip acts as a shield for preventing grain from lodging between the top edge of the bottom plate 4 and bottom edge of the portion 6 of the band 5. If ordinary hinges were employed, the grain would enter between the said parts when the bottom swings open to permit the excess grain to empty and the grain lodged between the bottom plate 100 and part to which it is hinged would thereby prevent the bottom plate from swinging back to closed position with the result that the bucket would leak and never carry its proper measure of grain.

From the foregoing description, taken in connection with the accompanying drawing,

the advantages of the construction and of the method of operation will be readily apparent to those skilled in the art to which the invention appertains, and while I have described 5 the principle of operation of the invention, together with the device which I now consider to be the best embodiment thereof, I desire to have it understood that the device shown is merely illustrative and that such 10 changes may be made when desired, as are within the scope of the claims.

Having thus described the invention, what I claim is:—

1. An elevator bucket having an automatically opening and closing bottom, a flexible supporting strip extending continuously across the whole length of the bucket for supporting the bottom and serving as a shield, and means for yieldingly holding the 20 bottom normally in closed position.
2. An elevator bucket provided with a bottom plate, a flexible strip to which the said plate is attached and extending continuously across the whole length of the bucket 25 and serving as a shield, and a spring arranged to normally hold the bottom in closed position.
3. An elevator bucket provided with a bottom plate, a flexible strip attached to the 30 top of the plate for supporting the same and extending continuously across the whole length of the bucket, and a leaf spring supported to normally hold the plate in closed position.
- 35 4. An elevator bucket comprising connected back and end plates, an inclined bottom plate, a band encircling the bucket at the upper edge thereof, a flexible strip secured to the band on which the bottom plate 40 is secured and extending continuously across the whole length of the bucket, and a leaf

spring attached to the band at one end and bearing at opposite end against the bottom plate to hold the latter yieldingly in closed position.

45

5. An elevator bucket comprising a sheet metal body bent into a back and end walls, a bottom plate disposed between the end walls and bearing against the bottom edge of the back wall, a flexible strip securing the 50 bottom plate on the body and extending continuously across the whole length of the bucket, and means for yieldingly holding the bottom plate in closed position.

6. An elevator bucket comprising a sheet metal body bent into back and end walls, a bottom plate disposed between the end walls and bearing against the lower edge of the back wall, a band encircling the upper portion of the body, a flexible member attached 60 to the band and bottom plate for flexibly supporting the latter and extending continuously across the whole length of the bucket, and a leaf spring disposed parallel with the end walls and secured at one end to 65 the band and bearing at its opposite end against the under side of the bottom plate.

7. An elevator bucket comprising a body composed of back and end plates, a cross member arranged at the outer corners of the 70 end walls to form a support, a flexible strip attached thereto and depending therefrom and extending continuously across the whole length of the bucket, a bottom plate secured to the strip, and a spring fixed on the cross 75 member and bearing on the bottom plate.

In testimony whereof, I affix my signature in presence of two witnesses.

ADOLPH W. BERKNER.
